ADDING MACHINE

Charles H. Bratt, Groton, N. Y., assignor to L. C.
Smith & Corona Typewriters, Inc., Syracuse,
N. Y., a corporation of New York

Application November 2, 1939, Serial No. 302,505

3 Claims. (Cl. 235—60)

Important objects of the present invention are to provide, in a key-set adding and recording machine, an improved keyboard and improved mechanism controlled thereby for recording transaction items or details in addition to recording transaction amounts; and to provide very simple and compact mechanism for said purpose.

Other objects of the invention will appear hereinafter.

In the drawings, Fig. 1 is a side elevation of an adding machine embodying the invention;

Fig. 2 is a vertical longitudinal section on the line 2—2 of Fig. 6, the section including the entire length of the machine;

Fig. 3 is an enlarged vertical transverse section approximately on the line 3—3 of Fig. 2;

Fig. 4 is a detail perspective view of certain elements of the machine forming part of the invention;

Fig. 5 is a detail sectional view showing the means for limiting accumulating rotation of one of the register pinions;

Fig. 6 is a top plan view of the keyboard and certain associated elements of the machine;

Fig. 7 is a rear view of the recording types of the machine;

Fig. 8 is a front elevation of the adding sector racks, the register pinions and associated parts, certain of said parts being in section;

Fig. 9 is a vertical longitudinal section on the line 9—9 of Fig. 6;

Fig. 10 is a vertical longitudinal section on the line 10—10 of Fig. 6; and

Fig. 11 is a detail section on the line 11—11 of Fig. 10.

The invention is illustrated as embodied in a portable adding machine of the type known commercially as the Corona adding machine, the construction and operation of which are substantially as shown and described in Barrett Patent No. 1,811,840 of June 30, 1931. In the present drawings machine parts corresponding to those disclosed in said patent are correspondingly numbered.

The machine has a main frame including a base plate 1 and upstanding side plates 5 and 6 rigidly secured in a fixed relation to each other and to the base plate. Said side plates support the entire mechanism of the machine, with the exception of the ribbon mechanism. A cover casing 8 encloses most of the machine and has the ribbon mechanism mounted thereon. The ribbon mechanism is indicated only in Fig. 1

and is designated R. A bracket for supporting a roll of paper P is mounted upon the rear side of the cover casing.

A keyboard unit extends between the upper forward margins of the frame side plates 5 and 6 and is supported thereon in a rearwardly and upwardly inclined position. The unit includes a frame comprising a top plate 12 and depending side plates 15. These side plates have apertures through which removable transverse rods 16 are passed to removably secure the unit in place.

The keyboard includes keys for recording a number of items and details of different transactions. There are keys for the commodity sold, keys for the quantity of the commodity sold, keys for the cash amount involved in the sale and keys for different clerks or salesmen. All of these different kinds of keys are conveniently and compactly arranged in the keyboard.

In the present instance the keyboard includes a right-hand bank of amount keys 18 and a left-hand bank of amount keys 18a. Said banks are spaced apart across the keyboard and each bank includes a plurality of rows or columns of keys numbered in each column from "1" to "9". In the present instance there are four columns of keys in the right-hand bank and three columns in the left-hand bank. All of said keys of both banks are both recording or listing keys and accumulating keys. At the lower end of each column there is also a key 18b. This key may be a zero key, but in the present instance it serves merely as a correction key to restore to normal position any key of an associated column which has been erroneously set. Between said banks of keys there is a short column of keys 18c alongside the right-hand bank, and a column of keys 18d alongside the left-hand bank and coextensive with the bank columns. The keys 18c and 18d are recording keys only. They do not control accumulation. In the present instance there are three of the keys 18c, marked "A", "B", and "C" and they may be employed to indicate clerks or salesmen in different transactions. Keys 18d are marked to indicate gasoline, oil, grease and other commodities sold. At the lower end of each of the columns of keys 18c and 18d there is also one of the correction keys 18b.

Each of the keys 18 to 18d inclusive has a flat stem 19 formed at its lower end with a narrow tail or stop finger 20. Some of the keys have the stop finger located centrally of the width of the stem and other keys have the

finger offset at one side or the other of the center so that the stop fingers are in staggered relation along a key column. The upper portions of the key stems are fitted in apertures in the plate 12 and the stop fingers are fitted in apertures in a narrow plate or strip 22. One of these strips underlies each column of keys and is secured within the frame of the keyboard unit. The respective key stems have elongated central openings 27 through which latch strips 28 extend, the respective latch strips having beveled notches and latch dogs 29, cooperating with a detent 30 formed in the respective keys by another hole 31 located above the opening 27. The latch strips are mounted within the frame of the keyboard unit for longitudinal sliding. When a key is depressed the latch strip will be slid toward the front of the machine until the key detent 30 is engaged by the under side of the latch dog 29. In this manner the keys are held in depressed or set position, but if, after a key is depressed, another key is depressed in the same row, the first key will be released and returned by a spring to normal position, thus forming a "flexible keyboard." Springs 33 are provided for restoring depressed keys to normal position. These springs are preferably coiled about rods 34, extending transversely of the rows of keys, between alternate keys of the rows. The ends of the springs extend in opposite directions and project into the holes 31 in adjacent key stems. Thereby a single spring is adapted to operate two keys.

The undercut notches of the beveled latch dogs 29 are shallow so that when the latch dogs engage the detents or cross bars 30 of the keys, the latch strips 28 will not fully return to their original positions, thereby holding the associated stop levers (37) hereinafter referred to, out of engagement with the corresponding adding units.

The side plates 15 of the keyboard unit have rearwardly projecting arms 35 forming the support for a transversely extending shaft 36 lying below the rear ends of the latch strips 28 for supporting a plurality of stop levers 37, pivotally mounted thereon and held in a spaced relation and with their upper ends in position to cooperate with the latch strips 28. The upper ends 39 of the stop levers 37 lie alongside the rear ends of the latch strips 28 and have laterally projecting ears 40 adapted to engage with the ends of the latch strips, as indicated in Fig. 2. The stop levers 37 are also provided with fingers 41, between which and holes 42 in the respective latch strips, double acting springs 43 are connected for holding the ears 40 in contact with the ends of the respective latch strips and for moving the latch strips toward the rear to effect latching of set keys or, when no keys are set, the spring will hold the latch strips 28 and stop levers 37 in normal position with the latter in position to engage the stops or detent teeth on the adding units.

The rod or shaft 36, supporting the stop levers 37, forms the pivotal support for a yoke or rock bail 44 adapted to lie immediately back of the rear ends of the latch strips 28 and to limit the rearward movement of the latter under the action of the springs 43. By stop means, disclosed in the aforesaid Patent No. 1,811,840, the bail is held against rearward movement from the position in which it is shown in Fig. 2. Thereby the bail holds the latch strips 28 against rearward movement under the influence of the springs 43.

Bail 44 has rearwardly extending arms 44^a pivotally supporting thereon a small auxiliary yoke or rock bail 46. This auxiliary bail is normally held in the position shown in Fig. 2 by a spring 49 (Fig. 6), extending between the bails, and by stop means, disclosed in the aforesaid patent. There is also provision, disclosed in the aforesaid patent, for operating the latch strip bail 44 to move all of the latch strips forward and thereby release any of the set keys at the end of a return stroke of a general operating handle.

In the repeat operation on machines of this character the number set up on the keyboard is retained while the handle is operated several times to repeatedly add the same number. For this purpose the auxiliary bail 46 is adapted to be moved toward the rear and held in that position for the "repeat" operation. There is a repeat key lever 52 of bell-crank shape pivotally mounted as at 53 upon a forwardly extending arm formed with bail 44. A rearwardly extending arm of the repeat key lever is formed with a cam edge 55, which is normally in engagement with the rear edge of the auxiliary bail 46, and a notch 56 located above said cam. The spring 49 connecting the bails 44 and 46 acts on the latter bail to press it against said cam and hold the repeat key lever in the position shown in the drawings. In that position an upwardly extending arm of the repeat key lever is in engagement with a stop lug 57 formed on said forwardly extending arm of bail 44, upon which the repeat key lever is pivoted. Said upwardly extending arm may be provided with a key cap.

In preparation for repeat operation of the machine the repeat key lever is swung clockwise, with reference to Fig. 2, to cam the bail 46 rearwardly, and lock it by means of the notch 56, and thereby swing a pin 51 borne by the bail 46 (see Fig. 6) out of reach of means disclosed in the aforesaid patent, for rocking the bails 46 and 44 forwardly, as the general operating handle approaches the end of its return stroke. Therefore the bail 44 is not operated to press the latch strips 28 forwardly and release keys which have been set. Consequently a number set up will be repeatedly printed upon repeated operation of the operating handle. The set keys are manually releasable by swinging the repeat key back to normal position, engaging its upwardly extending arm with the lug 57 on the bail 44 and pulling the lever forward to rock said bail, through the medium of the lug 57, and cause the bail to push the latch strips forwardly and release the set keys.

In order to prevent accidental release of set keys by jars or shocks to which they may be subjected, particularly in repeat operations, means are provided to lock the latch strips against key-releasing movement. The latch strips are provided with notches 59 near their rear ends. A locking bail 60 is provided for engagement with these notches to prevent movement of the latch strips after the operating handle has been started on its forward stroke. Bail 60 is pivotally mounted by arms 61 on the ends of the rear-most spring-supporting rod 34. The bail has a downwardly and rearwardly extending arm 62 to cooperate with a pin 63 carried on a lever arm operable by means disclosed in the aforesaid patent. The arrangement is such that in normal position of the operating handle the pin 63 by engaging the lower end of the arm 62 lifts and holds the locking bail out of engagement with

the notches 59 in the latch strips thereby permitting the keys to be freely set. After the handle has started and is on its forward stroke, the pin 63 will be moved out of engagement with the arm 62 thus permitting the locking bail 60 to engage the notches of the latch strips and prevent accidental movement thereof.

Adding units are rotatably mounted upon a transverse main shaft 68 to which the main operating handle of the machine is secured. The adding units comprise driver elements 69 carrying type bands 70. The type bands are formed as narrow rolled strips, concentrically mounted on arcuate flanges on the driver elements 69, the type being fixed thereon and adapted to be printed from by movement of a platen against the type. The driver elements 69 of the adding units are provided with upwardly projecting stop lugs 71 to cooperate with ears 72 bent over on the ends of the stop levers 37 which form part of the keyboard unit and are adapted to be positioned by the latch strips 28 when keys in the keyboard are depressed. The arrangement is such that when the keys are set, the ears 72 are lifted sufficiently to clear the ends of the stop lugs 71 thereby permitting rotation of the adding units when the handle is operated. Preferably the type segments and adding units are mounted in condensed form, for compact printing by the type, and, since the columns of keys are spaced farther apart than is required for the type segments, the rear ends of the stop levers 37 are bent inward to bring the ears 72 thereof into cooperative relation with the adding unit stop lugs 71.

The driver elements 69 are disc-like or sector-like and are secured to hubs 73. These are formed with pulley grooves, and driving springs 74 pass over the hubs and engage pins 75 secured to the respective driving elements 69, as indicated in Fig. 2. The opposite ends of the springs 74 are carried forward and anchored to a cross bar 77 extending between the side plates 5 and 6 and supported thereby. By this arrangement the driver or type sectors 69, and hence the adding units, are urged forward by the springs, but are normally prevented from forward movement by a bail hereinafter described. Depression of keys in the keyboard frees the units for forward movement by lifting the stop levers 37. The hubs 73 of the type segment driving elements 69 extend a short distance on the right side of the latter to form bearing shoulders 78 upon which adding sectors 79 are rotatably mounted. Said sectors 79 have arcuate slots 80 concentric with the shaft 68 and spaced therearound, and the driving elements 69 have headed rivets 81 extending through said slots and securing the adding sectors to the respective driving elements for independent rotation to the extent of one unit. Springs 82 resiliently connect together the driving elements and the adding sectors, the arrangement being such that the springs are adapted to move the adding sectors for transfer of tens, as more fully described hereinafter.

The movements of the adding units, after the stop levers 37 have been positioned by setting keys, are determined by the tail stops of the respective keys. For this purpose, the adding sectors 79 are provided with pivot studs 83 to which links 84 are pivotally connected. The opposite ends of the links 84 are pivotally connected by bolts 85 with stop slides 86 which are provided with stop lugs 87 adapted to engage the tail stops

20 of the key stems 19. The stop slides have elongated slots 88 and 89 cooperating with annular grooves in transversely extending rods 91 supported in the frame plates 5 and 6. The arrangement being such that the slides are held in proper spaced relation and are freely slideable for differential positioning of the respective adding units according to the setting of the keys. A transverse rod 91a is supported in the frame plates 5 and 6 and serves as an abutment engageable by depending tail portions of the slides to prevent the slides being accidentally moved out far enough to disengage the slots 89 from the rod 91.

15 The pins or bolts 85 of the links 84 are slidably mounted in the forward ends of the slots 88 of the respective stop slides 86 so as to permit relative longitudinal movement therebetween. Said pins are held normally at the forward ends of the 20 slots by means of springs 92 connected at one end to the links and at the opposite end to the slides. This arrangement provides a safety device to prevent injury to the machine in case a key is accidentally depressed during the return stroke of the operating handle. If that should occur one of the stop lugs 87 would engage the front side of a key tail stop 20 and thus prevent the return of the corresponding stop slide 86 with its associate adding sector 79, 25 which, as hereinafter described, is adapted to be returned to normal position when the driving elements 69 are returned by the pick-up bail, but this would merely stretch the spring and as soon as the return of the handle released the key the 30 spring would snap the stop slide back to normal position.

The lugs 87 on the stop slides 86 are in staggered arrangement along the slides in order to cooperate with the staggered tail stops 20 of the keys. The upper or rear stops on the stop slides 86, instead of being upwardly projecting lugs as at 87, are shoulders 95 and 96 on a folded-over angle projection on the stop slides. The stop slides are mounted in the machine at an angle of thirty degrees to the horizontal so as to slide in parallel relation to the under side of the keyboard unit, and the stop lugs 87 are disposed to clear the stop tails of the keys when the keys are in normal retracted position.

35 The adding sectors 79 are provided with segmental racks 107 concentric with the main shaft 68 and adapted to engage accumulators or register wheel pinions 108. These are rotatably mounted on a transverse rod or shaft 109 the 40 ends of which are supported in the side bars 110 of the accumulator rock frame. The register wheels have hubs 111 projecting from the left of the wheels and each wheel is flanked at its left side by a disk 112. Each hub bears a single tooth 114. These teeth form triggers for operating carrying levers or pawls in the transfer of tens. Said triggers are preferably slanting on one face and straight on the other and adapted to cooperate with ratchet-tooth-like noses 115 45 at the forward ends of carrying levers 116. These levers are pivotally mounted on a transverse shaft 117 supported in the accumulator unit side bars 110 and therefore are movable with the register wheels when the latter are moved out of and into engagement with the adding sector racks 107. The rear ends of the carrying levers have laterally projecting ears 119 adapted to 50 cooperate with forwardly projecting detent fingers 120 formed on the lower extremities of the respective adding sectors to limit return move-

ment of the latter and control transfer of tens. The accumulator rock frame is mounted on a transverse rock shaft 121 the ends of which are pivotally supported in the main side frame plates 5 and 6. The accumulator unit is adapted to be rocked with the pivot shaft 121 for moving the register wheels into and out of mesh with the adding sector racks 107.

The noses 115 of the carrying levers 116 have bevel forward faces for cooperation with the triggers 114 as the register wheels 108 are rotated during normal addition. Opposite the cam faces, the tooth-like noses 115 are straight and substantially radial as to the register wheels, to form detent latches for engaging corresponding radial faces on the triggers 114 when the register wheels are rotated in the opposite direction to re-set the accumulators to zero or take the total. When the register wheel pinions 108 are rotated more than nine units, during addition, the triggers 114 will engage the bevel faces on the ends of the carrying levers 116 and move the latter so that the opposite ends thereof will be moved out of the field of the detent fingers 120, thereby permitting the respective next higher order adding sectors to move forward an additional unit space under the pull of the transfer springs 82, for transfer of tens. Frequently the adding sectors and hence the detent fingers will not have returned to normal position at the time the carrying levers are tripped by the triggers 114. Therefore, means are provided for holding the carrying levers 116 in tripped position until the transfer of tens takes place. The carrying levers are provided with depending arms 124 having laterally projecting ears 125, adapted to cooperate with latch lugs or notches 126 on latch pawls 127. These pawls are pivotally mounted on a transverse shaft 128 supported in the side bars 110 of the accumulator rock frame. Double-acting springs 129 are provided for holding the carrying levers in position to be engaged by the triggers 114. The springs are anchored to the carrying levers and to the latch pawls and also serve to hold the latch pawls in engagement with the ears 125 when the carrying levers are displaced by the triggers.

After transfer of the tens, at the end of a return stroke of the handle, it is necessary to reset the carrying levers 116 for transfer of tens on the next return stroke of the handle, and this is done during the forward stroke of the handle. When the accumulator rock frame is moved downwardly to disengage the register wheel pinions 108 from the adding sector racks 107, the outer ends 132 of the latch pawls 127 are adapted to engage a transversely disposed fixed rod 133 which will lift the latches and thereby release the transfer levers 116 and permit them to return to normal position by the pull of the springs 129, provided the detent fingers 120 have been pushed back.

During the positioning movements of the adding sectors, the register wheel pinions are moved out of mesh with the adding sector racks 107 and, therefore the register wheels, being freely rotatable, are liable to become displaced. To avoid this, fixed detents 134 are mounted below the register wheels to engage the respective register wheels when the latter are moved out of mesh with the adding sectors. These detents are mounted on transverse rods supported by and between the main frame plates 5 and 6. The detents have upwardly projecting tooth-like noses to enter between the teeth of the respec-

tive register wheels. In order to limit the rocking movements of the accumulator unit the rock frame side bars 110 are provided with forked forward ends, the lower fingers 138 being engageable with a fixed transverse rod 139 supported in the main frame plates 5 and 6, to limit movement of the pinions toward the adding sector racks. The upper forwardly extending ends 138a of the side bars 110 are engageable with the bar

10 139 to limit the movement of the accumulator rock frame when the register wheels are withdrawn from the adding sectors. The side bars 110 are secured rigidly together by transverse rods 140.

15 In the present instance there are ten of the type bands 78 mounted upon the respective driving segments 68 and each bearing a vertical series or column of type characters facing rearwardly. Fig. 7 is a rear face view of the type bands and type. The characters of the four columns 78a at the left, with reference to Fig. 7, are amount characters, from "0" to "9" inclusive and their set-up for listing or recording is controlled by the keys 18 of the right-hand bank 20 in the keyboard. The second column 78a from the left in Figure 7 includes decimal points. The type band immediately to the right of said four series bears, along its lower portion, a short column 78c of amount type characters from "1" to 25 "5" inclusive. The upper portion of said band also bears a short column of type characters 10a and including "A," "B" and "C." The selective set-up of these letter characters for printing is controlled by the keys 18c. The different letters 30 may be employed to designate clerks or salesmen, for example, while the amount characters sharing the same type band with the letter characters, together with the series of amount characters 78a at the left thereof in Figure 40 7, may be employed for printing dollars and cents. The purpose of said short series of amount characters is solely for printing the overflow or carry-over from the columns at the left, with reference to Fig. 7, when a total is taken.

45 The type band immediately to the right in Figure 7 of the band bearing the short column of amount characters and letter characters bears a series of commodity-identifying type characters 78e whose set-up for printing is controlled 50 by the keys 18d. The three type bands immediately to the right in Figure 7 of the last-mentioned band bear columns of amount type characters 78f whose set-up for printing is controlled by the keys 18a on the keyboard. The first of 55 said three columns includes the characters "1" to "9" inclusive, with a decimal point before each character. The two following columns include the characters "0" to "9" inclusive. At the right in Figure 7 of said three columns the final type 60 band has a column 78g of amount type, characters "1" to "9" inclusive, whose purpose is solely that of printing the overflow or carry-over from the three columns immediately at the left thereof, with reference to Fig. 7, in total taking.

65 With reference again to Fig. 7, there are six columns of characters having zeros and the zeros are located at the upper ends of the respective type bands and in horizontal alignment across the type assembly. Suitable known zero-eliminating means may be provided to prevent printing of the third, fourth, fifth or sixth zero, from the left, with reference to Fig. 7, when no number is set up in an adjacent column of higher denomination. Such an eliminating means is 70 not illustrated as it forms no part of the present 75

invention. The two zeros in the cents columns, at the left in Fig. 7, may be allowed to remain in position for printing at each operation of the machine for listing and also for total-printing. The topmost type character in the commodity-designating series 70^e is also located at the same level as the zeros and provision is made to prevent printing therefrom, when its respective control key is not set. To that end, the particular driving member 69 which bears the commodity type characters has its stop, which cooperates with one of the stops 72, set in advance of the stops 71 of the other members 69, as indicated at 71^a. When the operating handle of the machine is swung forward for a printing operation all of the members 69 are operated by the springs 74 to swing the type bands 70 upward toward printing position. The said forwardly set stop 71^a however engages its respective stop 72 early in its movement so that the stop 72 prevents movement of the topmost commodity type to the printing point. The topmost of the "A," "B," "C" types is located below the level of the zero types so that no mechanism is required to prevent the topmost letter type from printing when its control key is not set. As will be seen in Fig. 7 there is also a gap, one character space in length, between the lowermost letter type and the first of the amount types sharing the type band with the letter types.

At the rear of the type segments there is a platen 141. The printing paper is trained around the platen and the platen is rockably supported to move the paper thereon against the inking ribbon R', indicated in Fig. 2, and press the ribbon against the type for printing. The platen is rotatably mounted between frame side plates 142 which are secured together by transverse stay rods to form a rock frame which is mounted upon a transverse rock shaft 146, borne by the main frame side plates 5 and 6. The platen frame plates 142 have forwardly projecting lugs 152 to engage a fixed transverse rod 153 mounted in the main frame plates 5 and 6 for limiting rearward movement of the platen. The lower extremities of the platen frame plates 142 are formed as stop fingers 155 to cooperate with a transverse stop rod 156 to limit movement of the platen toward the type segments. By means such as disclosed in the aforesaid patent, the platen may be rocked toward the type segments for printing when the operating handle is swung on its forward stroke, and swung away from the type segments when the handle is swung on its return stroke. Suitable means, such as disclosed in said patent, may be provided for training the paper around the platen and for rotating the platen for line-space feeding of the paper.

As previously described herein, one of the type sectors bears both the letter characters "A," "B" and "C" and the amount characters "1" to "5" inclusive, the selective set-up of said letter characters for printing being controlled by the setting of the non-accumulating keys 18^c, and the set-up of said amount characters being controlled by the accumulating means which cooperate with the right-hand bank of keys. In order to accommodate the machine to the improved keyboard and to the location of said letter characters and amount characters upon a common type segment the adding and accumulating means are modified over those disclosed in the aforesaid patent.

The adding sector associated with said type sector which bears both letter type and amount

type has a rack 107^a provided with fewer teeth than the racks 107 of the adding sectors to the right thereof. In the present instance there are twelve teeth upon said racks 107 and only seven complete teeth upon the rack 107^a. The teeth upon the rack 107^a include an uninterrupted row of five complete teeth 107^b extending inward from the forward end of the rack and one complete tooth 107^c at the rear end of the rack. At 10 the inner side of said row of teeth and at the inner side of said single tooth there is also a tooth stub 107^d of slight depth. Between said stubs there is a gap 107^e. This gap is so located that when the rack 107^a is in normal position the rear portion of gap will be directly over the associated register wheel 108. The length of the gap is sufficient to permit movement of the rack to a degree permitted by setting of any one of the letter keys 18^c without rotation of the register wheel by the rack. That renders said keys recording keys only; they cause no accumulator operation. When, however, the rack is released and moved forward by its spring 82 to carry over a ten, the tooth 107^c will rotate the register pinion 108 one tooth space to accumulate the ten upon the pinion. The tooth stubs 107^d are merely to aid meshing of the teeth 107^b and 107^c with the teeth of the register wheel.

Means are provided for positively limiting accumulating rotation of the register pinion 108, associated with the mutilated rack 107^a in accordance with the limited amount-printing capacity of the associated type segment. Means are also provided to hold said pinion against accidental rotation. Mounted forward of the register wheels 108 there is a bracket 384 formed of a strip of stiff sheet metal bent to provide it with a straight medial portion 385 extending transversely of the machine, a rearwardly and upwardly extending left arm portion 386 and a similarly extending right arm portion 387. The left arm has an aperture registering with an aperture in the forward end portion of the left-hand accumulator frame plate 110 and a bolt 388 is passed through said aperture and has a nut screwed thereon, to secure the bracket 384 to said frame plate. The left arm of the bracket is also formed with a finger 389 extending rearwardly and upwardly beyond the screw hole and bent to the left, as at 390, to engage the upper edge of said plate 110 and prevent turning of the bracket clockwise, with reference to Figs. 2 and 4. The right arm 387 of the bracket bears a headed screw 391 upon which a detent pawl 392 is pivoted intermediate its ends. This pawl is located directly in front of the register pinion 108 which is associated with the mutilated rack 107^a, and the lower end of the pawl is rounded, as at 393, and formed to fit between adjacent teeth of the register pinion to hold the latter against rotation. A spring 394 connects the upper end of the pawl to an upwardly extending lug 395 formed on the arm 387 of the bracket and acts to yieldably hold the pawl in retaining engagement with the register pinion. The pinion is thereby held against accidental rotation but it may be rotated by the rack 107^a.

Bracket arm 387 is also formed with a rearwardly and upwardly extending finger 396 having at its extremity a downwardly depending stop tooth 397. Said stop tooth is disposed in the path of the trigger tooth 114 fixed to rotate with said pinion. Normally, when the adding machine is clear the trigger is in engagement with the rear 75 side of the nose 115 of the associated carrying

lever 116. As the pinion is rotated for accumulation of carried-over tens the trigger is moved until it and the pinion are finally stopped by engagement of the trigger with the stop tooth 397. The latter is disposed to positively limit the rotation of the pinion to five tooth spaces, for accumulating five tens, that number corresponding to the number of amount type characters borne by the type segment which also bears the letter characters "A," "B" and "C."

In order to further adapt the adding mechanism to the improved keyboard said mechanism is designed to prevent accumulating action by the particular sector 79 which is under the control of the commodity keys 18^d. To that end no register pinion is provided for cooperation with said sector. That renders the keys 18^d recording keys only; they cause no accumulator operation. Also, as previously pointed out, the adjacent pinion to the right, which cooperates with the mutilated rack 107^a has its accumulating rotation limited to five tooth spaces. Consequently its trigger 114 can never move far enough to trip the particular transfer lever associated with the said commodity sector 79 so that transfer movement 25 of the sector is prevented.

Near the upper right-hand corner of the keyboard there is a total key 253. At the right-hand side of the keyboard there is a clear key 260, marked "Chg" for "charging." Spaced downwardly alongside the keyboard from said clear key there is also a non-print key 236.

The general operating handle of the machine is designated 196. It is detachably affixed to the right-hand end of the main shaft 68 and normally occupies a rearwardly swung position. A universal rock bail, or adding unit pick-up bail 294 is rotatably mounted upon a medial portion of the shaft 68 and is normally located in front of the shaft in position to cooperate with noses or stop edges 295 carried by and formed as part of the type sector discs 69. The latter, as previously pointed out, form the drive elements of the adding units. In response to forward movement of the handle the pick-up bail will be moved counter-clockwise, as viewed in Fig. 2 by means disclosed in the aforesaid patent. This will permit the adding sector units to move forward differentially according to the setting of the keys in the keyboard. When the handle returns, the bail 294 will pick up the respective adding units, by engaging the noses 295 and restore the driving elements 69 to normal position against the action of their springs 74. The movements of the handle and the bail will be controlled by suitable means such as disclosed in the aforesaid patent.

In the operation of the machine it may be assumed, for illustration, that it is desired to record a transaction including the sale of five and one-half gallons of gasoline by a salesman identified by the letter "B" and for the amount of \$1.25. The following keys are depressed: The key "5" in the units column of the left hand bank of the keyboard, the key "5" in the decimal column of said bank, the key "Gas" in the commodity column and the appropriate keys "1", "2" and "5" in the dollars and cents columns of the right-hand bank of the keyboard. Depression of these keys disposes their stop tails in the path of the appropriate stops 87 on the appropriate slides 86 and also elevates the proper stops 72 to free the appropriate adding sectors and type sectors for movement. When the operating handle is swung forward the accumulator unit 75

will, by means such as disclosed in the aforesaid patent, be rocked downward to demesh the register wheels 108 from the racks of the adding sectors, and the bail 294 will be rocked to permit the freed adding sectors and type sectors to move counter-clockwise, as viewed in Fig. 2, as far as the stop tails of the set keys will permit. Thereby the appropriate type will be brought to printing position. The forward movement of the handle, by means such as disclosed in the aforesaid patent, causes the platen to be swung forward and it reaches printing position when the handle is at or near the limit of its forward movement. Thereby the amount of the commodity sold, the identification of the commodity, the identification of the salesman and the monetary amount of the transaction are all printed in one line across the paper.

When the handle starts its return movement 20 the accumulator unit, by means such as disclosed in the aforesaid patent, is caused to rock upward and bring the register pinions 108 into mesh with the racks 107. As the handle swings rearward the bail 294 is caused to swing clockwise, as viewed in Fig. 2, and the bail restores the type sectors 69 and the adding sectors 79 and their racks to normal position thereby causing the adding racks to rotate the register pinions and accumulate the amounts thereon.

When the totals are to be taken the handle is first moved through an idle forward stroke and return stroke. That is in order to restore to normal position any of the transfer levers 116 which may have been latched out by the preceding adding and listing operations of the machine, as set forth in the aforesaid patent. Then the clear or charging key 260 is depressed and may be latched down by means such as disclosed in the aforesaid patent. At the same time the total key 253 is pressed rearward and held and the handle is swung on a forward stroke. By means responsive to operation of the total key and the clear key and such as disclosed in the aforesaid patent, the accumulator unit is caused to remain in normal position and hold the register pinions in mesh with the racks 107 as the handle is swung forward. Thereby the adding sectors and type sectors are placed under control of the accumulating means to set up the type for printing the totals, the racks rotating the pinions clockwise to bring their triggers 114 back into engagement with the rear sides of the noses 115 of the transfer levers 116, thereby clearing the machine. Means such as disclosed in the aforesaid patent cause the accumulator unit to be rocked downward to move the register pinions out of mesh with the racks when the handle is started on its return stroke after total printing. Near the end of the return stroke the accumulator unit is rocked upward to remesh the pinions with the racks. As the handle is returned, the bail 294 is rocked to restore the adding sectors and type sectors to normal position.

If, when a total is taken, no tens have been transferred for printing by the amount type borne by the type segment which also bears the clerk-identifying letters, Fig. 7, said segment will be rocked upwardly to bring the gap between said letter types and said amount types to the printing point so that no printing will be done from this segment. Said idle rocking of the segment is permitted by the gap 107^e in the associated mutilated rack 107^a. Operation of the total key causes all of the stops 72 to be lifted to inoperative position by means disclosed in the aforesaid.

patent. Consequently, since the gap 107^a in said rack is normally over the associated register pinion 108, the pinion has no control over the rack until the rack moves sufficiently to bring one of the rack teeth 107^b into mesh with the teeth of the pinion. Since the trigger 114 fixed to the pinion is then against the rear side of the nose 115 of the associated lever 116 the pinion is locked against clockwise rotation and it in turn limits the movement of the rack, the adding sector and the type segment. The rack is so designed as to stop the type segment in a position with said gap therein at the printing point. If, on the other hand, tens have been transferred to said register pinion the trigger will have been moved counter-clockwise away from its stop 115. Then, for total printing the rack teeth 107^b will rotate the register pinion back until the trigger reengages its stop 115 and the type segment will thereby be stopped in position for printing from the proper amount type.

When a credit sale is made and it is desired not to include the amounts in the total the charging key 260 is depressed and the handle swung forward and back. On the forward stroke of the handle the machine will operate as in adding and listing. On the return stroke, however, by means such as disclosed in the aforesaid patent, the accumulator unit will be rocked downward, after momentarily rocking upward at the beginning of the return stroke of the handle, to shift the register wheels out of mesh with the racks and prevent accumulations of the numbers set up on the keyboard. The numbers however will be printed in the usual way.

It is sometimes desirable to eliminate the printing operation. In that case the non-print key 236 is depressed. By means such as disclosed in the aforesaid patent, the means for rocking the platen to printing position are disabled so that the platen remains in its rearwardly swung position.

In order to take a sub-total the handle is moved through a forward idle stroke and back. Then the total key 253 is pressed rearward and the handle is swung on a forward stroke and a return stroke. By means controlled by said key, and such as disclosed in the aforesaid patent, for example, the accumulator unit may be controlled to mesh the register pinions 108 with the racks 107 during both the forward stroke and the return stroke of the handle. Clearing of the machine is thereby prevented.

What I claim is:

1. In a key-set adding and listing machine including a shiftable adding rack, a bank of amount keys settable selectively to limit shift of said rack differentially, and a shiftable type carrier bearing amount types appropriate to said keys and responsive to shift of said rack to set one of said types, appropriate to a set one of said keys, in preparation for printing, in combination, a shiftable mutilated higher-order rack, a special designation key settable to limit shift of said higher-order rack, a shiftable higher-order type carrier bearing a lesser number of amount types than said first carrier, for extended total printing only, and also bearing a special designation type appropriate to said special designation key, said higher-order carrier

being responsive to shift of said higher-order rack as limited by said special designation key setting to set said special designation type in preparation for printing, a lower-order accumulator pinion and a higher-order accumulator pinion shiftable into and out of mesh with said first rack and said higher-order rack respectively, the higher-order rack having certain of its pinion-rotating teeth omitted in accordance with said lesser number of amount types, to prevent rotation of the higher-order pinion in the shift of the higher-order rack between the limit determined by the setting of said special designation key and the normal position of the rack, and means to actuate the higher-order rack for carrying over tens from the lower-order pinion to the higher-order pinion.

2. In a key-set adding and listing machine of the class described having a shiftable adding rack, a column of amount keys settable selectively to limit shift of said rack differentially, and a shiftable type carrier bearing amount types appropriate to said keys and responsive to shift of said rack to set one of said types, appropriate to a set one of said keys, in preparation for printing, in combination, a shiftable higher-order rack, a shorter column of special designation keys at the left of said first column and settable selectively to limit differentially shift of said higher-order rack, a lower-order accumulator pinion and a higher-order accumulator pinion engageable with said racks for adding and total taking operations, a shiftable higher-order type carrier bearing a lesser number of amount types than said first carrier, for extended total printing only, and also bearing special designation types appropriate to said special designation keys, said higher-order carrier being responsive to shift of said higher-order rack to set one of said special designation types appropriate to any set one of said special designation keys in preparation for printing, the latter rack having a gap in its series of teeth reducing the number of teeth, for the purpose set forth, and so located on the rack and of such extent as to avoid rotation of the higher-order pinion by the higher-order rack in the shift of the latter between the limit determined by the setting of any one of said special designation keys and the normal position of the rack, and means coactive with the higher-order rack to control the latter automatically to carry tens from the lower-order pinion to the higher-order pinion, said higher-order rack tooth series comprising a tooth at one side of said gap to mesh with said higher-order pinion for carry-over and teeth at the opposite side of the gap to mesh with the higher-order pinion for total-taking.

3. In a key-set adding and listing machine as claimed in claim 2, means to positively limit rotation of said higher-order pinion in accumulating direction to prevent accumulation thereby of a number of tens exceeding the number of amount types on the higher-order type carrier, and yieldable detent means to prevent accidental rotation of the higher-order pinion while the gap in the tooth series of the higher-order rack is opposed to said pinion.
